UNITED STATES PATENT OFFICE.

CLARENCE E. BONNER, OF NEW YORK, N. Y., ASSIGNOR TO RENNOBEC COMPANY, OF DOVER, DELAWARE, A CORPORATION OF DELAWARE.

PNEUMATIC TIRE.

Application filed July 5, 1923. Serial No. 649,405.

To all whom it may concern:

Be it known that I, CLARENCE E. BONNER, a citizen of the United States, residing at New York, in the county of New York and 5 State of New York, have invented certain new and useful Improvements in Pneumatic Tires, of which the following is a specification.

This invention relates to a new and improved pneumatic tire and more particularly to a pneumatic tire assembly adapted to automatically close up punctures and to prevent escape of air from the tube.

It is well known in the art that inner tubes 15 can be rendered self-healing by being formed with a thickened tread portion and being reversed when stripped from the mandrel so that the inner portion of the tread is held under compression by the tensile strength 20 of the outer portion of the tread. However, it has been found in practice that it is necessary to provide some means for increasing the tensile strength of the outer portion in order to provide adequate compression of 25 the inner portion of the tread.

Various means have been devised for providing this increased tensile strength as, for example, imbedding a layer of fabric in the tread. This method, however, is open to objection in that the tube is subject to rupture 30 at the edge of the fabric. A further difficulty lies in the fact that the fabric being substantially non-stretchable it is necessary to make it of exactly the same length as the inner circumference of the casing with which 35 it is to be associated. Otherwise there is a tendency for the tube to twist in the casing.

It is an object of the present invention to provide a new and improved tire assembly 40 wherein adequate compression is afforded in the tread portion of the inner tube without the reinforcement of the tube itself by any incorporated foreign tensile means.

It is a further object to provide a construction of this character in which the inner tube may be readily adapted for use with standard outer casings without alteration 45 therein.

It is an additional object to provide a construction utilizing an inner tube which may 50 be readily formed at small cost and which is adapted to adjust itself to variations in the

form and contour of the outer casing with which it may be associated.

Other and further objects will appear as 55 the description proceeds.

I have illustrated a preferred embodiment of my invention in the accompanying drawings, in which—

Figure 1 is a cross section of a casing with 60 a deflated inner tube therein;

Figure 2 is a section showing the tube inflated;

Figure 3 is a perspective illustrating the 65 method of forming the tube; and

Figure 4 is a cross section of the inner tube showing its normal position when deflated.

As shown in Figure 3, the tube 11 is formed upon the mandrel 12 and is provided 70 with the thickened tread portion 13. The tube is stripped from the mandrel by reversing it upon itself as shown in Figure 3 so that the outer surface is put under tension and the inner surface under compression. 75 The two ends of the tube are then joined in the usual manner.

The greater thickness of the tread 13 and its resistance to compression will cause the finished tube to assume the shape shown in 80 cross section in Figure 4 when deflated. If this tube be used in the casing in the usual manner, when pierced by a puncturing element, there will be a tendency for the compressed inner portion of the tread to close 85 tightly about the entering element and to close again to close up the opening when the element is withdrawn. However, if the tube be not provided with reinforcing means associated with the tread surface, there is 90 also the tendency for the material to tear due to the puncturing rupture and due to the tensile stress set up in the outer surface layers of the tube by the compression of the inner layers.

I counteract this latter tendency by securing the tread portion 13 of the tube to the inner surface of the tread portion 14 of the casing 15 by means of an adhesive 16. This adhesive is brushed into the tread of 100 the casing before the tube is placed therein and, when the inner tube is inflated, it is intimately pressed against the adhesive. This adhesive is of such strength as to effectively

prevent relative movement between the two surfaces which it joins. Consequently, when the tube is punctured the tensile strength of the outer portion of the tube is reinforced by the strength of the casing itself and the tearing of the tube at the point of entry of the puncturing material is effectively prevented. The inner portion of the tread is therefore properly held under compression and closes up the opening and prevents loss of the pressure in the tube.

This adhesive is, however, preferably of such a nature as to permit the tube to be manually stripped from the casing when it is desired to remove the tube for inspection or repair. It will be readily apparent that if a relatively weak adhesive is used, it may be entirely adequate to prevent relative movement of the tube and casing parallel to the two contacting surfaces and yet permit the surfaces to be torn apart without injury to either surface.

In this form of tire assembly an inner tube is used entirely without reinforcing material and which can be made rapidly at relatively small cost. The tube may be used in existing types of casings without alteration therein. It may be readily and quickly applied and installed in the casings and when so installed provides a self-healing construction.

I claim:

1. A pneumatic tire assembly comprising an outer casing, an inner tube in said cas-

ing, and an adhesive of relatively small strength securing said casing and tube together.

2. A pneumatic tire assembly comprising an outer casing, an inner tube in said casing, and an adhesive of relatively small strength securing the tread portions of said casing and tube together.

3. A pneumatic tire assembly comprising an outer casing, an inner tube in said casing, the inner tube having a thickened tread portion, and an adhesive securing said tube tread portion to the inner surface of the casing tread, said adhesive being of sufficient strength to prevent relative movement between casing and tube, but permitting the tube to be manually stripped from the casing without injury to tube or casing.

4. A pneumatic tire assembly comprising an outer casing, an inner tube in said casing, the inner tube having a thickened tread portion, an inner portion of said tread being maintained under compression by an outer portion thereof, and an adhesive securing said tube tread portion to the inner surface of the casing tread, said adhesive being of sufficient strength to prevent relative movement between casing and tube, but permitting the tube to be manually stripped from the casing without injury to tube or casing.

Signed at New York, New York, this 6th day of June, 1923.

CLARENCE E. BONNER.
